UNITED STATES PATENT OFFICE

2,150,005

DENTAL SEPARATOR AND MATRIX HOLDER

Frank B. McNinch, Philadelphia, Pa.

Application December 28, 1937, Serial No. 182,047

10 Claims. (Cl. 32—64)

My invention relates to a new and useful dental separator and matrix holder and has for one of its objects to provide an exceedingly simple, effective and inexpensive device of this character having means to engage several parts of contiguous teeth to prevent dislodgment or slipping of the device in any direction so that the effective separating and holding action will not be interrupted.

10 Because of the general napiform shape of a person's teeth, the usual resilient devices placed between contiguous teeth have a tendency to work in, out, forward or backward and become displaced relative to the occlusal surfaces of the teeth or actually dislodged from between the teeth. To overcome these defects or faults, I construct the article of my invention so as to include means cooperating with the proximal surfaces of the teeth to prevent the web thereof from "creeping" inward and other means cooperating with the inner and outer surfaces of the teeth thereby preventing "creeping" of the web in any direction. The particular arrangement or location of the elements relative to one another positively maintains the web between the occlusal surfaces and therefore will accomplish the purposes desired. Consequently, another object of the present invention is to make a device of this character including a web having a head along one edge and longitudinally spaced retaining means on both faces adjacent its other edge.

15 With the above and other objects in view, this invention consists of the details of construction and combination of elements hereinafter set forth and designated by the claims.

20 In order that those skilled in the art to which this invention appertains may understand how to make and use the same, I will describe its construction, referring my numerals to the accompanying drawing, in which:—

25 Fig. 1 illustrates a pair of teeth with my invention applied thereto.

Fig. 2 is a section thereof longitudinally of the teeth.

Fig. 3 is a transverse sectional view on the line 3—3 of Fig. 2.

30 Fig. 4 is an enlarged perspective view of a dental separator and matrix holder according to the invention.

Fig. 5 is an end view thereof.

35 Fig. 6 is a perspective view of the strip from which the device of the invention may be cut as desired or required.

In carrying out my invention as herein embodied 10 represents the dental separator and matrix holder which is substantially T-shaped in cross section and consists of a web or body 11 with a head 12 along one edge and protuberances 13, 14, 15 and 16 projecting from the faces of the web or body adjacent the edge of the web opposite the head. The protuberances are arranged so that one pair, as 13 and 15 project from one face and the other pair, as 14 and 16 project from the other face of said web. The protuberances on one face are located directly opposite those on the other face all of which may be readily observed by reference to Fig. 3. If desired, the protuberances may be limited to one face.

45 The device is made from elastic, waterproof material, such as rubber or like materials and is applied by distending the web and its head until said web becomes sufficiently thin to permit its insertion between a pair of teeth 17 and 18 or between a tooth and a matrix assembled in the usual or any well known manner. In placing the 50

5 device the head is inserted between the proximal surfaces of the teeth and the protuberances engage the inner and outer surfaces of the teeth between the occlusal surfaces thereof and the gum, said protuberances preferably being dome shaped to produce a wedging effect on the teeth.

10 A still further object of the invention is to make the stock, from which the combined dental separator and matrix holder may be cut, in strip form and having many protuberances on both faces of the web, those on one face being located directly opposite those on the other face.

15 With the above and other objects in view, this invention consists of the details of construction and combination of elements hereinafter set forth and designated by the claims.

20 In order that those skilled in the art to which this invention appertains may understand how to make and use the same, I will describe its construction, referring my numerals to the accompanying drawing, in which:—

25 Fig. 1 illustrates a pair of teeth with my invention applied thereto.

Fig. 2 is a section thereof longitudinally of the teeth.

Fig. 3 is a transverse sectional view on the line 3—3 of Fig. 2.

30 Fig. 4 is an enlarged perspective view of a dental separator and matrix holder according to the invention.

35 Fig. 5 is an end view thereof.

Fig. 6 is a perspective view of the strip from which the device of the invention may be cut as desired or required.

In carrying out my invention as herein embodied 10 represents the dental separator and

matrix holder which is substantially T-shaped in cross section and consists of a web or body 11 with a head 12 along one edge and protuberances 13, 14, 15 and 16 projecting from the faces of the web or body adjacent the edge of the web opposite the head. The protuberances are arranged so that one pair, as 13 and 15 project from one face and the other pair, as 14 and 16 project from the other face of said web. The protuberances on one face are located directly opposite those on the other face all of which may be readily observed by reference to Fig. 3. If desired, the protuberances may be limited to one face.

45 The device is made from elastic, waterproof material, such as rubber or like materials and is applied by distending the web and its head until said web becomes sufficiently thin to permit its insertion between a pair of teeth 17 and 18 or between a tooth and a matrix assembled in the usual or any well known manner. In placing the 50

5 device the head is inserted between the proximal surfaces of the teeth and the protuberances engage the inner and outer surfaces of the teeth between the occlusal surfaces thereof and the gum, said protuberances preferably being dome shaped to produce a wedging effect on the teeth.

60 A further object of the invention is to produce a T-shaped device of elastic, waterproof material such as rubber or the like, and including a web or body for insertion between the teeth, a head

device in position the edge of the web, adjacent which the protuberances are located, is inserted between the teeth and forced inward relative to the teeth until the head 12 contacts the proximal surfaces of the teeth as plainly illustrated in Fig. 2. This prevents the device from being inserted too far and stops said device from creeping or slipping forward towards the papilla of the gum. When the device is positioned and the distending force removed therefrom, the web will contract and draw a companion pair of protuberances at one end of said web into engagement with the inner surfaces and the other companion pair of protuberances at the opposite end of said web into engagement with the outer surfaces of the pair of teeth being operated upon and below the occlusal surfaces.

By making the sides of the head inclined or beveled as indicated at 19 said head will snugly fit the proximal surfaces of the teeth, as shown in Fig. 2 and by making the protuberances dome shaped the tension of the web tends to cause said protuberances to wedge in between the teeth and therefore produce a continuous separating action. As there is a pair of protuberances at both the front and back of the teeth, said protuberances prevent the device from creeping inward and outward and since said protuberances engage the surfaces of the teeth between the largest transverse diameter of the teeth and the gum, the device is prevented from creeping or sliding rearward. In actual practice, the device is of such size that the edge of the web adjacent which the protuberances are located will be spaced from the papilla of the gum and due to the fact that the device is held against displacement it can never come in contact with the papilla and cause soreness.

A number of the devices may be embodied in a strip as shown in Fig. 6 which strip will be of the same cross sectional shape as a single device, but there will be a series or row of protuberances on one or both faces and said strip can be cut into sections in a manner that will provide a pair of the protuberances on either or both faces and said cutting may be done whenever desired or as the devices are required.

Although I have described the invention generally as having protuberances on both faces of the web it is to be understood that those on one face can be dispensed with or the protuberance at one end may project from one face of the web and the protuberance at the other end may project from the opposite face.

While I have described the use of the device particularly as a separator, it will be obvious that the same may be utilized as a matrix holder in which the retaining action of the head and protuberances will be similar to that hereinbefore outlined.

Of course I do not wish to be limited to the exact details of construction herein shown and described as these may be varied within the scope of the appended claims without departing from the spirit of my invention.

Having thus described my invention, what I claim as new and useful is:

1. A dental separator and matrix holder comprising a member of elastic material T-shaped in cross section and including a web adapted to be inserted between contiguous teeth, a head along one edge of said web, and a pair of protuberances

on each face of said web adjacent its opposite edge each one of said protuberances being adjacent to an end of said web.

2. The structure in claim 1 in which the protuberances are dome shaped.

3. The structure in claim 1 in which the sides of the head are beveled inwards towards the web.

4. A device of the kind described comprising a member of elastic material T-shaped in cross section and consisting of a web that can be stretched so as to decrease its thickness for insertion between the teeth, a head along one edge of said web adapted to engage the proximal surfaces of the teeth and prevent displacement of the device toward the gingival surface, and a pair of oppositely disposed protuberances at each end of the web adjacent the edge thereof opposite the head and adapted to engage the inner and outer surfaces of the teeth past the greatest cross-sectional area of the teeth to prevent inward or outward displacement of the device.

5. The structure according to claim 4 wherein the head has inwardly beveled sides and the protuberances have curved surfaces to produce a wedging effect on the teeth due to the contractile action of the web.

6. A dental appliance of elastic material adapted to utilize the generally napiform shape of the teeth to hold it in place and consisting of a web for insertion between the teeth, a V-shaped head to engage the contiguous surfaces of the teeth above the occlusal surfaces, said web and head combined being of less height than the exposed portions of the teeth between which it is to be used therefore to prevent contact with the papilla, and spaced dome-shaped protuberances on both faces at both ends adjacent the edge of the web opposite the head and adapted to engage the inner and outer surfaces of the teeth below the occlusal surfaces.

7. A dental appliance comprising a strip of elastic material of T-shape in cross section thereby providing a web and head, and a series of longitudinally spaced protuberances on each face of the web adjacent the edge opposite to the head, said strip adapted to be cut into sections having a pair of the protuberances on each face of the web.

8. A dental appliance comprising a member of elastic material T-shaped in cross section to provide a web and a head along one edge of said web, and a pair of spaced protuberances on both faces adjacent the other edge of said web, the protuberances on one face being directly opposite those on the other face.

9. A dental appliance comprising a member of elastic material T-shaped in cross section and consisting of a web, a head along one edge of said web, and a pair of protuberances on one face adjacent the opposite edge of said web each one of said protuberances being adjacent to an end of said web.

10. A dental appliance comprising a member of elastic material T-shaped in cross section and consisting of a web, a head along one edge of said web, a protuberance on one face of said web at one end, and another protuberance on the other face of said web at the opposite end, said protuberances being located adjacent the edge opposite the head.
